United States Patent Office.

JOHN DORNAN, OF PHILADELPHIA, PENNSYLVANIA.

Design No. 4,294, dated August 16, 1870.

DESIGN FOR A CARPET PATTERN.

The Schedule referred to in these Letters Patent and making part of the same.

I, JOHN DORNAN, of the city of Philadelphia, in the State of Pennsylvania, have invented and produced a new and original Design for Carpets, of which the following is a specification.

The nature of my invention or design is fully represented in the accompanying photographic illustration, to which reference is made.

The said illustration represents one of four-like quarter sections of a square, in which the figure in the corner A will form a quarter part of the center or configuration constituting my design.

Claim.

I claim as my invention—
The design for a carpet, as shown.

JOHN DORNAN.
